UNITED STATES PATENT OFFICE.

SALLY AIRO, OF DETROIT, MICHIGAN, ASSIGNOR TO LINCOLN MANUFACTURING COMPANY, OF DETROIT, MICHIGAN, A CORPORATION OF MICHIGAN.

DESIGN FOR A BEAM-LIGHT FIXTURE.

Application filed June 14, 1926. Serial No. 18,030. Term of patent 7 years.

To all whom it may concern:

Be it known that I, SALLY AIRO, a citizen of Finland, residing at Detroit, county of Wayne, State of Michigan, have invented a new, original, and ornamental Design for a Beam-Light Fixture, of which the following is a specification, reference being had to the accompanying drawing forming part thereof.

Figure 1 is a side elevation.

Figure 2 is an inverted plan view.

I claim:

The ornamental design for a beam light fixture, as shown.

SALLY AIRO.
